United States Patent Office.

JOSEPH B. HARRIS, OF GERMANTOWN, KENTUCKY.

Letters Patent No. 71,300, dated November 26, 1867.

FIRE-PROOF PACKING FOR SMOKE AND HOT-AIR FLUES.

The Schedule referred to in these Letters Patent and making part of the same.

TO ALL WHOM IT MAY CONCERN:

Be it known that I, JOSEPH B. HARRIS, of Germantown, in the county of Mason, and State of Kentucky, have invented a new and useful Improvement in Safety-Jackets for preventing steamboat chimneys and other metal smoke or fire-flues from setting fire to wooden decks, floors, or walls, or other inflammable substances in close proximity thereto; and I do hereby declare that the following is a full, clear, and exact description of the construction and operation of the same, reference being had to the accompanying drawings, and to the letters of reference marked thereon.

Figure 1 is a vertical section of a steamboat chimney, and of my safety-jacket as applied thereto, and

Figure 2 is a plan view of a cross-section in line x x , fig. 1.

A is the chimney. B is the wooden deck. C is an annular series of air-chambers surrounding the chimney. D is another annular series of chambers surrounding C, and concentric therewith, and filled with a non-conducting substance, hereinafter described. E is an outer case or jacket surrounding the whole. F is a shield, packed with the same non-conducting substance to protect the under side of the deck from the heat of the flue between the chimneys, and from the heat of the furnace-mouth. Said annular series of air-chambers C is formed by interposing a corrugated plate, c, between two cylindrical plates, thus dividing the space between them into a number of separate chambers, c'; but it is manifest it may be divided otherwise, as by radial partitions, or in any other way that will form a series of air-spaces or flues all around the chimney. These air-spaces c' are to be open at both ends, above and below the deck, at o o', or when passing horizontally through a wall, on both sides of the wall.

The annular space D may be divided into separate chambers d, in the same way as the inner annular space C. These outer chambers d are all to be packed tight with a fire-proof and non-conducting substance, composed of the residuum of bituminous schist or shale, prepared in accordance with Letters Patent of the United States granted to me, and bearing date July 3, 1866, No. 56,044, and as follows, to wit: I take schist or shale, formed in connection with bituminous coal having but little bitumen in it, and subject it to heat, in a retort or kiln, till all the bituminous and volatile substance has been expelled, and the residuum has been reduced to friable and pulverous condition of a light ash or pearl color. This pulverous residuum is then bolted through a fine bolt to free it of all lumps or gritty or combustible particles, when it is ready for use in carrying into effect this invention. This substance should be packed into the chambers d in a heated condition, and when all dampness has been thoroughly expelled said chambers are to be closed air-tight at both ends, by metal plates or coverings; but if the packing is not perfectly dry, before closing them, there will be danger of their bursting from the steam generated from the moisture.

It is not absolutely necessary that the annular spaces C and D should be divided into separate chambers, as described, although I prefer to so divide them; and some kind of stays, between the outer and inner cylinders, will be found necessary, if tight partitions are not used.

The inner annular space C, or annular series of chambers c', will always have a current of air passing through, which will have a tendency to reduce the heat of the chimney or pipe, and check the conduction of heat to the outer drum D; while said outer annular space D, or annular series of chambers d, being packed with the non-combustible and slow conducting substance herein described, will render it impossible for the most intense heat of the chimney or pipe to ignite the most combustible substances in direct contact with the outer portion of this safety-jacket.

The fire-proof substance or packing, herein described, may be produced from semi-bituminous coal, treated in the manner herein described, but I prefer schist or shale.

When this safety-jacket is to be applied to large pipes, liable to become intensely heated, as steamboat chimneys, the annular spaces C and D should be from three to five inches wide, but for small pipes, of thinner metal, spaces of less width will suffice.

The shield F is formed by attaching a concave plate of sheet metal to the lower side of the deck, and packing the concavity with the same fire-proof material herein described. It is manifest that a similar shield will be applicable to many similar uses, as to prevent the heat of any stove or furnace from being communicated to any wooden or other combustible wall or floor in close proximity thereto. It may be formed by packing a space

between two metal plates, with said fire-proof material, or a space between a metal plate and the floor or wall to be protected.

Having thus fully described my invention, what I claim, and desire to secure by Letters Patent, is—

1. A safety-jacket, for surrounding or enclosing any metal flue for conducting smoke or heat, containing an annular air-space or series of air-spaces, and an annular space or series of spaces packed with the fire-proof material herein described, the same being constructed and arranged substantially as herein set forth.

2. I also claim in a safety-jacket or shield, to prevent the conduction or radiation of heat from pipes, stoves, furnaces, or fires of any kind to adjacent combustible substances, an intervening space packed with the fire-proof material herein described, substantially as and for the purpose set forth.

J. B. HARRIS.
